UNITED STATES PATENT OFFICE.

WALTER B. ALLEN, OF BOSTON, MASSACHUSETTS.

COIN-CONTROLLED KEY-LOCKING KEEPER.

SPECIFICATION forming part of Letters Patent No. 593,065, dated November 2, 1897.

Application filed March 17, 1897. Serial No. 627,954. (No model.)

To all whom it may concern:

Be it known that I, WALTER B. ALLEN, a citizen of the United States, residing at Boston, in the county of Suffolk and State of Massachusetts, have invented a new and useful Coin-Controlled Key-Locking Keeper, of which the following, together with the accompanying drawings, is a specification sufficiently full, clear, and exact to enable persons skilled in the art to which this invention appertains to make and use the same.

My present invention relates, primarily, to the organization of mechanism for locking and for controlling the unlocking of holding-jaws or grip devices, the object being to provide a keeper for securing bicycles or other articles temporarily left in charge, said mechanism embracing suitable holding appliances and a key-locking means combined with a coin-controlled device for primarily releasing or permitting operation of said key-locking means and its key, thereby rendering the key-lock available to the person desiring to place an article in temporary security, as more fully hereinafter explained.

Another object is to provide a mechanism for the purpose named comprising, in combination, a pair of gripping fingers or jaws, a key-locking means for securing said fingers or jaws in closed relation, an intervening device for normally preventing action of said lock, and also confining the jaws, coin-controlled devices that release said parts, and means for automatically resetting the parts to non-operative position after one usage of said locking appliances.

Another part of my invention relates to the combination, with coin-controlled key-locking appliances for the purpose named, of a registering mechanism the object of which is to indicate the number of times that the lock has been used during any given period.

Another part of my invention relates to the construction and arrangement, as more fully hereinafter explained, of the appliances for the introduction and reception of coins, the object being to provide a mechanism that will automatically discard small coins, iron disks, and similar spurious material without effecting an operation of the lock-releasing mechanism.

These objects I attain by the mechanism

illustrated in the accompanying drawings, wherein—

Figure 1 is a plan view of mechanism embodying my invention. Fig. 2 is a vertical section at the top of the case, showing a portion of the coin-race. Fig. 3 is a vertical section of the case, showing a side view of the mechanism. Fig. 4 is a front view of the mechanism, the jaws being in section; and Fig. 5 is a sectional front view illustrating the action.

This invention as herein shown is more especially designed as a keeper for bicycles and is provided with jaws, holders, or grip devices shaped for clasping the rim and tire of a bicycle-wheel. Said holders or grip devices can, however, when desired, be shaped for holding any other kind of article for which this class of mechanism is required.

Referring to the drawings, A indicates the case or frame for containing the operating parts, which comprise a pair of holding devices or jaws B, a key-operated locking bolt or bar C, adapted for confining and releasing said jaws, and a coin-controlled block or device D, arranged for normally confining both the key-locking mechanism and the holding-jaws and operated for releasing the same upon the introduction of a proper coin. The proper coin for the purposes of this invention will be denominated a "five-cent piece" or "nickel;" but it will be understood that this mechanism can, if in any instances desired, be arranged for control by a coin of other denominations without departure from the nature of the invention or changing the mode of operation.

The holding fingers or jaws B are each provided with a head portion formed with a straight lateral face b or suitable surface for engagement by the lock, and said jaws are pivoted to swing laterally upon a stud or bolt a, fixed in the bed-plate A'. A suitable spring E is best arranged in connection with the heads of the jaws for returning said jaws to their normal central and closed position after they have been opened. Said spring is shown as secured to the bar at e, with its free ends respectively pressing outward against the backwardly-forked ends of the jaw for swinging the same against stops or lugs a', fixed in the plate.

The lock-frame C' is strongly fixed upon the bed-plate A' in such relation to the faces b of the jaws that its bolt C when thrown forward will rest against or stand closely adjacent to said faces.

The lock mechanism may be of any suitable construction, as desired, but is arranged with a key-stop c², consisting of a lug or pin fixed to the frame and projecting into the keyway, so as to limit the rotation of the key when the bit has been turned back sufficiently for the retraction of the lock-bar and has its keyhole 4 so located that the key K can be withdrawn from and inserted in the lock only when the lock-bar C is at its forward or locked position. The head of the lock-bar C may be made laterally broad, or so as to match the engaging faces b on the jaw-heads. An upright lug or pin 3 is fixed on the fore end of the lock-bar, and a similar lug or pin 5 is fixed on the rear part of the head of the outer jaw B.

An interposable piece, which I will term the "dog-block" D, is adapted to freely drop into the space between the side faces b of the jaw-heads and the end face of the lock-bar. This dog-block is connected to or forms a part of a lever D', which is fulcrumed at f in a swivel post F to have upward and downward leverage and lateral swinging movement. The rear part of the lever extends to the coin-drop chute G, and is provided with a projecting part or tongue d, that extends laterally through a slot 6, formed in said chute, and which tongue is adapted for intercepting the coin dropped therein, as indicated by dotted lines, Fig. 3. Said slot affords a sufficient space for the free swing of the lever to the required limit of its movement.

The dog-block D or head of the lever may be made hollow for lightness and the rear end extended and provided with adjustable counterweights 7, preferably screw-threaded upon the extended end of the lever D'.

H indicates the coin-race, and I the slide plate or gate for carrying the coin from the exterior to the drop-chute G, which is arranged to receive the nickel through the proper-sized opening G' in the race H, turn the same so its disk will stand in vertical plane, and to conduct said coin onto the tongue d and into a chamber or receptacle J, beneath the bed-plate. The race is provided with a smaller preceding opening L, that communicates with a chute L', through which any small-sized coins, as one-cent pieces, will drop and be delivered, as at L², into a compartment or receptacle J', separate from the coins by which the lock mechanism is controlled. The slide-gate I is provided with the usual hole i for receiving the coin, and is adapted to be drawn out to the position i² (indicated by dotted lines) to facilitate the deposit of a coin therein, and to be then moved back until its end strikes the stop h, at which position the hole i of the gate coincides with the hole G' of the chute G.

Arranged over the coin-gate I, at suitable

distance therefrom, I provide a magnet M, secured in place with its under surface preferably flush with the inner surface of the case A. At one side of the race H, I provide a lateral passway and a corresponding semi-circular space n through the bottom thereof into a chute N, that leads to a discharge- orifice N', preferably opening to the exterior at the rear or bottom of the case. An inclined rib or shoulder m is arranged across the race-way above the gate I and just forward of the side opening or space n, said incline directing toward said space. The rear end of the gate is provided with an upwardly-projecting lip m² and a cut-away space n², that substantially corresponds with the space n when the gate is at outward position. The upper edge of the lip m² moves along the under surface of the magnet and casing when the gate is operated, closely adjacent, but preferably without bearing contact therewith.

In some instances it is desired to record the number of times the keeper is used, and for such purpose a registering mechanism is combined therewith for operation as follows: Said mechanism preferably comprises a register-drum O, adapted for supporting a strip of paper P about its periphery, which is corrugated or grooved to permit of the paper being readily punctured. The drum O is connected with a screw-threaded hub O', that is mounted in a stationary bearing R, adapted for engaging said screw-thread, and upon a splined shaft S', turning in said bearing and having fixed thereon a ratchet-wheel S. A pawl T, connected with the lock-bar C, is arranged for moving said ratchet one notch at each reciprocation of the lock-bar, and a suitable guard-pawl t is provided to prevent backward movement of the ratchet-wheel. An adjustable guard t² may be employed for causing the pawl to engage but one tooth at a time.

A prick-finger Q is provided upon a moving part of the keeper mechanism, (preferably a slightly-resilient finger attached to the swivel-post E,) and said finger is provided with a sharp point or marker that swings into contact with the face of the register-drum and makes an impression or puncture in the paper strip when the parts are operated, as herein-after explained. The pawl and ratchet imparts intermittent motion to the shaft S'. Accordingly the register-drum is rotatively advanced step by step, and at each rotation is slipped longitudinally upon the shaft by the action of the screw-thread, so that the line of punctures for the succeeding rotation will be offset from the preceding line of punctures a distance equal to the pitch of the screw. The register-drum is provided with means u for securing and releasing the ends of the paper P, which is arranged about the face thereof and can be taken off and renewed as occasion may require. The register-drum can be removed and replaced, as occasion requires, for changing the paper strip by rais-

ing the bearing-cap, which may be hinged and latched, as indicated in Fig. 5, or other suitable means.

The operation is as follows: The parts being in position as indicated in full lines in Figs. 1, 3, and 4, in which position the jaws or fingers B are held from opening movement by the dog-block D, any person desiring to lock up his wheel draws out the gate I, bringing its hole *i* to the position *i'*, deposits a nickel therein, and slides in the gate. When the hole *i* of the gate reaches the hole *G'* in the raceway, the nickel drops down the chute G, striking the tongue *d* of the dog-block lever D', and by gravity of the coin depressing the same in the slot 6, thereby actuating the lever and raising the dog-block D from between the jaw-heads and lock-bar, as indicated by dotted lines in Figs. 3 and 5, while the tongue intercepts and retains the nickel at the slot 6. The jaws or fingers B are then free to be spread or opened, (see dotted lines Fig. 1,) so that the rim of the bicycle-wheel can be inserted between them. After entering his wheel-rim between the jaw-fingers B the operator turns the key K of the lock C', throwing forward the lock-bar C, so that its face strikes the side faces *b* of the jaw-heads, closing or forcing the jaws B together and effectually locking the same with the wheel-rim or article held securely within the grip. By the movement of the lock-bar C the pin 3 is advanced against the side of the dog-block D, swinging said dog and its lever D' laterally on the vertical axis of its swiveled fulcrum-post F to a position substantially as indicated by dotted lines, Fig. 1, and in Fig. 5. This lateral movement withdraws the tongue *d* from the slot, allowing the intercepted nickel to pass down into the receptacle J. The movement also forces the prick-finger Q against the paper P. When the parts are thus locked, the operator can remove the key K from the lock, put it in his pocket, and go about his business or pleasure, leaving his bicycle secured in the grip of the keeper mechanism until such time as he may choose to return. In the meantime if any one attempts to effect operation of the lock by introduction of a nickel the coin merely passes into the receptacle J, as it is not intercepted by the tongue *d*, the holding devices or jaws being at such time under control of the key-lock only.

When the person having the key returns for his wheel, he inserts the key in the lock and, turning, it throws back the lock-bar, thereby releasing the grip of the keeper-jaws and at the same time advancing the ratchet-wheel and register-drum one notch by the action of the pawl T. The keeper-jaw being released the action of removing the wheel or article therefrom spreads the jaws apart and the pin 5 swings against the side of the dog-block D, moving it to a position above the intermediate space and swinging the tongue *d* of the lever D' into the slot 6 of the coin drop-chute

G. The spring E forces the jaws together as the wheel is freed therefrom, and the dog-block drops into the intermediate space between the lock-bar C and face *b* of the jaw-heads, thereby locking the jaws against opening until again released. After the dog-block falls into position the key-lock cannot be worked nor the key K removed therefrom until said dog-block is raised by the introduction of a proper coin or nickel in the chute G, as above explained.

In case a person inserts a small coin or cent it drops through the hole *L'* and is directed by the chute into the compartment J' without effecting any operation of the mechanism.

In case it is attempted to work the mechanism by means of an iron or steel washer or disk inserted in the gate I such disk is drawn up from the opening *i* of the gate and held by the magnet M without passing to the drop-chute G. Then when the gate is again drawn out the lip *m* scrapes the disk *W* from the magnet (see Fig. 2) and, in conjunction with the inclined shoulder *m*, shoves said disk or washer laterally over the cut-away space *n*, so that it falls through the chute N and is ejected from the case at the exit-opening N', or, if desired, into some suitable receptacle connected with said exit.

As the lever D' is swung laterally the point of the prick-finger Q is carried toward the register-drum and caused to puncture the paper arranged about said drum. (See dotted lines, Fig. 1). Each time the lock is worked a puncture is made at a new place, and as the drum revolves the lines of puncture are offset by the endwise motion caused by the screw O'. The paper P is placed on the drum O and started at zero, and when the case is opened for collection the paper strip is removed and shows a series of rows of perforations, the number of which shows the number of nickels to be accounted for.

The lever D', with the dog-block D and the adjustable counterpoise-weights 7, act as a weight for the coin, and can, by adjustment of the poise, be made to operate or resist operation within a very close margin to the exact gravity of the class of coins designed to be used in any instance for controlling the mechanism.

In practice the case A or a series of such cases, each containing a like organized mechanism, is attached in any suitable manner to a bench or standing support of convenient height for receiving the bicycle-wheels, these stands being located at such situations as the public accommodation may require.

I claim as of my invention and desire to secure by Letters Patent—

1. The jaws or gripping-fingers adapted for receiving and embracing the rim and tire of a bicycle-wheel, in combination with a key-operated locking mechanism for holding said jaws closed, and a coin-controlled locking and releasing dog that normally confines said

parts and is primarily releasable for permitting operation of the lock by the key, substantially as set forth.

2. In combination with holding-jaws, grip-fingers or keepers adapted for retaining a cycle-wheel or other article; a key-operated lock that locks and unlocks said jaws, grip-fingers or keepers, a dog-block that automatically locks said jaws when the key-operated lock is retracted and also prevents action of said key-lock, and means for releasing said dog-block controlled by introduction of a proper coin.

3. The lock mechanism operated by a removable key, said key removable when the lock-bar is at locked position; in combination with the pivoted holding-jaws adapted to be secured by said lock-bar, an intervening coin-controlled device that engages and arrests movement of both said lock and jaws, and means actuated by the drop of a coin thereon, whereby said device is raised from intervention with said locked parts.

4. In mechanism for the purposes set forth, the combination of the key-operated lock-bar, the pivoted holding-jaws, the jaw-retracting springs, and opposing stops, and a coin-controlled dog-block fitted to enter between the lock-bar and jaw-heads.

5. In combination, the grip-fingers or jaws pivoted upon the bed, their pivot-heads fitted with stop-faces, the key-operated lock fixed on said bed, its lock-bar adapted to shoot against said stop-faces, the guide-pins respectively fixed on said lock-bar and the outer jaw-head, the tilting lever carrying a dog-block that corresponds to the space traversed by the lock-bar head, and having the coin-intercepting tongue, the swivel-post supporting the fulcrum of said lever, and the coin drop-chute having a slot for the entrance and movement of said intercepting-tongue, substantially as set forth.

6. In combination with the keeper-jaws and the key-operated lock-bar; the dog-block and tiltable dog-block lever fulcrumed in the swiveling post, said lever having a tongue for intercepting the coin, and provided with adjustable counterpoise devices, for the purpose set forth.

7. In a coin-controlled mechanism, the combination with the gate race or way by which the coin is introduced, and a sliding gate

therefor, of a side exit-passage and an over-head magnet located between the point of entrance and the coin drop-opening, and means for clearing off the under surface of said magnet, brought into action by the movement of said sliding gate, for the purpose set forth.

8. The combination with the coin gate-race, of the side exit-passage and waste-chute N, the overlying magnet, the front stop-shoulder m, and the sliding gate provided with a lip or flange m^2 at its inner end, substantially as set forth.

9. The combination, with the gravity-actuated lever that releases the locked mechanism, having a tongue that intercepts the fall of the coin; of the gate-race provided with the side exit n, the small coin-pass L' and the regular drop-opening G' arranged in the order shown, the drop-chute leading to the main receptacle and having a slot for the lever-tongue, the chute L for small coins, the overlying magnet M, the waste-chute N, the laterally-inclined shoulder m, and the slide-gate I having the opening i and the upwardly-projecting transverse lip m^2 , for the purposes set forth.

10. The combination with the jaws, the key-operated lock, the dog-block and its lever adapted to have lateral movement; of the register wheel or drum adapted for supporting a paper strip, its shaft and ratchet-wheel, the pawl connected with the lock mechanism, and the marking point or finger operating in conjunction with said register-drum, for the purpose set forth.

11. The register-drum having a screw-threaded hub or surface, a supporting-bearing engaging said screw-thread, the splined drum-shaft, the actuating-ratchet therefor, and its pawl operating in conjunction with the lock-bar, and the marking point or finger mounted on the dog-block-lever support; in combination with the locking-bar, the coin-controlled dog-block lever and parts secured thereby, substantially as set forth.

Witness my hand this 13th day of March, 1897.
